CLAIM

The ornamental design for a boat cover, as shown and described.

DESCRIPTION

FIG. 1 is a front and top perspective view of a boat cover, showing my new design;

FIG. 2 is a rear and bottom perspective view thereof;

FIG. 3 is an enlarged front elevation view thereof;

FIG. 4 is an enlarged rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged perspective view of detail “9” identified in FIG. 1.

The dashed lines in the figures illustrate portions of the boat cover that form no part of the claimed design. The dash dot dash lines in FIGS. 1 and 9 are for the purpose of illustrating the enlarged view indicators and form no part of the claimed design.
